UNITED STATES PATENT OFFICE.

ARTHUR LEE EASTIN, OF ST. LOUIS, MO., ASSIGNOR OF TWO-THIRDS TO AL
PHONZO WHIPPLE AND JOHN L. POLLARD, BOTH OF SAME PLACE.

PROOF-TAKING ROLLER MACHINE.

SPECIFICATION forming part of Letters Patent No. 352,049, dated November 2, 1886.

Application filed January 15, 1886. Serial No. 198,689. (No model.)

To all whom it may concern:

Be it known that I, ARTHUR LEE EASTIN, of the city of St. Louis, in the State of Missouri, have invented a certain new and useful Improvement in Proof-Taking Roller Machines, of which the following is a full, clear, and exact description, reference being had to the accompanying drawing, forming part of this specification, and in which the figure is a perspective view of my proof-taking machine, with part broken away to show the means of attachment of the spiral-spring shaft which carries the knife, and represents the manner of operating the machine.

My invention relates to a machine for taking proof hectograph copies; and my invention consists in features of novelty hereinafter fully described, and pointed out in the claims.

Referring to the drawing, A represents one of my proof-taking machines, B the frame in which the roller runs, and C the handle, the manner of grasping which is shown by the operator's hand in dotted lines at D.

E represents the main shaft or axle on which the roller runs. It works in bearings F near the lower extremity of the pendent arms B' of the frame B. A cylindrical sleeve, G, surrounds the shaft E, and serves as a bobbin on which the paper roll H is wound. This roll can either be filled on the machine by friction-rolling, or may be filled by any suitable machine for winding rolls preparatory to its insertion in the frame.

H' is the paper composing the roll. In active operations the latter mode of filling is preferable, as a number of the bobbin-sleeves can thus be filled and kept in stock ready for insertion in the machine without stopping to refill the roller.

I represents the knife, which serves the double purpose of severing the proof-sheets by its edge I', (after the impression is taken,) and as a clamp or follower to keep the paper intact and prevent its loosening on the roll during the process of unrolling and proof-taking. The knife-clamp is secured to a sleeve, J', that embraces and runs on a spindle-shaft, J, which has bearings K' in bracket-arms K, the said arms being secured by rivets or screw-bolts K' to the top bar, B', of the frame. The loop or bar L', in conjunction with the

spiral springs L, that are wound around the spindle-shaft, enforces the clamping of the knife-plate against the roll.

M represents the flask, and N the form of type or the hectograph-plate from which the impression is to be taken. The machine is especially adapted both to taking proof and also hectograph copies, &c.

By the use of my machine the faces of the type are not damaged, as they frequently are by hammering on the blocks in the usual manner of proof-taking; neither are the backs of the sheets soiled, as they are by blocks, or defaced by the dirty sponge, and no deep impressions are made through the back of the proof-sheets, for the pressure from the roller is distributed evenly over the whole surface, having a progressive motion instead of a dead pressure, without any jar like that produced by the hammering process. The paper is not required to be cut into sheets (as in the present practice) previous to taking the impression, and in consequence does not become soiled by handling (the machine doing the handling) or wasted by the use of a needless amount of paper, which in my machine remains clean in the roll until the impression is made, and is then readily severed by the knife exactly where required.

The operation of the machine is as follows: The paper roll is not dampened, as is necessary in the customary manner of proof-taking, but is placed dry in the machine and takes a dry proof, the novel features in its application enabling the proof-sheet to appropriate the ink from the type without the necessity of using the capillary attraction of moisture in the paper. The machine makes use of capillary attraction in another and more convenient way, (enabling it to take a dry proof.) The progressive action of the roller, like that of the pen in writing, draws on the ink in the same manner as the pen with its progressive motion distributes it. This is as truly illustrated in writing a single letter with a pen as with a word, for it is well known that if a non-conductor (such as grease, for instance) on the paper or pen breaks the thread of the capillary attraction the flow of ink is stopped and the remainder of the letter is not produced; besides which the progressive man-

ner of laying the proof-sheet by my roller removes the ink from the type to the sheet far more effectually than can be done by any dead pressure, as in the present manner of taking proof. The proof-sheet roll being placed in the machine, the operator, taking hold of the handle, as illustrated by the hand in dotted lines, commences at the foot of the form and rolls the proof-sheet over the type, pressing 5 down on the machine at the same time, and by the one operation thus taking an almost instantaneous proof, by which, although the operation is quickly performed, the impression is also well defined.

15 I have made the frame of malleable iron and the knife-blade of steel-plate and of width and proportions suitable for common proof-taking operations; but it may be made of any other suitable material and size without departing 20 from the essential features of my invention.

I claim as my invention—

1. In a proof-taking machine, the combination of the frame B, operating-handle C, main axle E, with bobbin-sleeve G, the shaft working in bearings F, with pendent arms B² of the frame arranged to carry the proof-sheet roll H and distribute the sheet over the face of the type and take proof-impressions therefrom,

all substantially as described, and for the purpose set forth.

2. In a proof-taking machine, the combination of the frame, bobbin-sleeve for the proof-roll, with the axle on which it runs, with the knife-clamp I, and spiral springs L on the axle J, all arranged to distribute the proof-sheet 35 over the face of the type and take an impression thereof, substantially as and for the purpose set forth.

3. In a proof-taking machine, the combination of the frame with its axle, the bobbin-sleeve for the proof-roll running in the frame, with the knife arranged to clamp the roll and sever the proof-sheets when the impression is taken, substantially as described, and for the purpose set forth.

4. In a proof-taking machine, the combination of the frame and a spindle running in the frame, said spindle arranged to carry a proof-reel, unroll the proof-sheet, and impress it over the face of the type and take proof-impressions thereof, substantially as set forth.

ARTHUR LEE EASTIN.
